UNITED STATES PATENT OFFICE

OSCAR S. SWALL, OF ROSS, CALIFORNIA, ASSIGNOR TO S & D LOOSE LEAF CO., LTD.,
A CORPORATION OF NEVADA

LOOSE LEAF BINDER

Application filed October 28, 1929. Serial No. 403,085.

This invention relates to loose leaf binders and has for its object improvements in such binders whereby a simple, effective and easily operated binder is realized, together with certain specific advantages of construction appearing in the drawing and following description.

In the drawing accompanying this application Fig. 1 is a plan view of my improved binder lying fully opened and with one cover broken away and with the inner facing material of the other cover partly broken away so as to reveal the construction.

Fig. 2 is a cross-section of the cover as seen along the line 2—2 of Fig. 1.

Fig. 3 is a cross-section of the cover as seen along the line 3—3 of Fig. 1.

Fig. 4 is an enlarged cross-section of the cover as seen along the line 4—4 of Fig. 1.

Fig. 5 is an enlarged cross-section of the cover as seen along the line 5—5 of Fig. 1.

In the drawing 1 designates one of the binder covers and 1' a portion of the other cover, cover 1 being the one which carries the adjusting mechanism for releasing and clamping the leaves 1'' (assumed in the view to be standing straight upward).

The leaves are apertured by slotting in the common manner of loose leaves and are aligned on ropes 2 passing through the slots of the leaves and through clamping bars 3 arranged at opposite sides of the leaves.

The ropes are countersunk and secured at one end each to cover 1' by means of countersunk plates 4 held in place by screws, nails or rivets 5 one or more of which pass through the ropes as indicated.

The bodies of the cover are of wooden boards 6 about a half-inch thick and preferably laminated as indicated in Figs. 2 and 4, and which boards are hollowed out by passing over a shaper to form elongated depressions 7 therein for the ropes and a large central depression 8 for the operating mechanism and hand of the operator, and the inner face of the board is lowered adjacent depression 8.

The mechanism comprises a cross-bar 9 firmly riveted or otherwise secured at its opposite ends to the ropes and a ratchet gear

10 rollable along a rack bar 11 extending longitudinally in the central depression and having its ends 11' countersunk in depressions formed in the wood.

The ratchet gear is carried by a block 12 secured to the underside of bar 9 and rolls along the rack as the bar 9 is grasped with the fingers and manually pulled outward of the cover to tighten the clamping bars 3 against the leaves. A spring pawl 12' locks the gear from reverse movement and may be released by pressure of a finger of the bar operating hand against a protruding button 13 upon grasping the bar 9 by the fingers of the bar operating hand for effecting movement of the bar. The particular feature of the present invention in connection with this part of the binder is the extension of the gear hub 14 through the face of bar 9 and the provision of a cross slot 15 in the hub so that it may be forcibly turned as by screw driver or ten-cent piece inserted into the slot so as to take up the slack and get a better clamping action on the leaves than otherwise possible.

The clamping bars are of sheet-steel and of L-shape in cross-section as best shown in Fig. 4 and in which figure it will be seen that the outer cloth or leather cover 16 of the binder covers extends over the outer and confronting faces of these clamping bars and is cemented or otherwise secured thereto. The paper sheets or leaves are clamped between the leather (or other material) facing the bars, and a fullness of the covering material is left between the bars and their respective covers as shown at 16' so that dust and dirt is excluded while the covers are free to open and close, though attention is called to the fact that this fullness is not the hinge of the covers but that the covers are each definitely hinged to the clamping bars by metal straps 17 countersunk and secured at their outer ends to the wooden bodies of the covers, and at their inner ends coiled around pins 18 extending between lugs 19 struck outwardly from the sheet-metal of the clamping bars.

Where the ropes pass slidably through the bars I provide rounded grommets 20 clinched in place, and I also cut out notches in the

short legs of the bars at 21 to clear the ropes yet give a high rib to stiffen the bar.

At the extreme ends of the L-shaped clamping bars I provide a moulded soft rubber plugs 22 riveted or otherwise secured to the bars as at 23 and the plugs having enlarged projecting heads 24 which in using the book will take the shock of dropping it about to thus avoid injury both to the book and to the desk.

In finishing my book I fold the covering material inward over the margin of the wooden boards, glue same in place and then cover the inside with a piece of stiff paper or cardboard 25 pasted in place and provided (for cover 1) with a cut-out matching the depression 8, and left free over the sliding elements.

I lay particular stress on the use of wooden boards hollowed out on one side for the mechanism in the manner shown as a valuable feature of my invention as it greatly facilitates manufacture, and yields a firmer and more durable structure.

I claim:

1. In a loose leaf binder, a pair of covers, a leaf clamping bar adjacent the hinge end of each cover, flexible tensioning devices extending from the inside of the covers through the bars, a covering of flexible sheet material pasted to the outer face of each of the covers completely covering each outer face thereof and extending rearwardly therefrom in an unbroken sheet over the outer and clamping surface of the adjacent bar and secured thereto.

2. In a structure as specified in claim 1, a portion of said sheet material preserved in a free loop between the edge of the cover and the bar.

3. In a loose leaf binder, a pair of covers, flexible binding elements extending between the inner faces of the covers, leaf-clamping bars through which said elements extend made of sheet-metal and provided with grommets surrounding said binding elements.

4. In a loose leaf binder, a pair of covers, flexible binding elements extending between the inner faces of the covers, leaf-clamping bars through which said elements extend made of sheet-metal of substantially L-section with said elements passing through the long arms thereof and the short arms being notched for the elements.

5. In a loose leaf binder, a pair of covers, flexible binding elements extending between the inner faces of the covers, leaf-clamping bars through which said elements extend made of sheet-metal of substantially L-section with the long arms in clamping relation for the leaves of the book, and hinge elements secured to the covers extending beyond the binding margin of the covers pivotally connected to said bars and a sheet of flexible covering material pasted to the outer face of each of the covers extending over the outer

face of the adjacent bar and along the clamping face of the long arm thereof.

6. In a loose leaf binder, a pair of covers, flexible binding elements extending between the inner faces of the covers and manually operable means for tensioning the elements including rack and pinion and a cross bar movable in one of said covers attached to the elements and adapted to be grasped by the fingers of a hand of the operator for movement, said rack extending freely through said cross bar transversely thereto and secured to the cover and said pinion carried by the cross bar engaging the teeth of the rack, a spring-influenced pawl normally tending to remain in engagement with said pinion at all times to permit movement of the pinion in one direction only, and a finger release for said pawl projecting outwardly beyond an edge of the cross bar adjacent the pinion adapted to be operated by the pressure of a finger of the bar operating hand upon grasping the cross bar by the bar operating hand for movement thereof.
